UNITED STATES PATENT OFFICE.

CLARA BORGENSCHILD, OF RACINE, WISCONSIN.

NURSING-BOTTLE.

SPECIFICATION forming part of Letters Patent No. 593,830, dated November 16, 1897.

Application filed July 17, 1897. Serial No. 644,911. (No model.)

To all whom it may concern:

Be it known that I, CLARA BORGENSCHILD, a citizen of the United States, residing at Racine, in the county of Racine and State of Wisconsin, have invented new and useful Improvements in Nursing-Bottles, of which the following is a specification.

My invention relates to improvements in nursing-bottles.

10 The object of my invention is to provide a form of bottle in which rubber tubes are dispensed with and which may be easily kept clean and free from all impurities.

15 In the following description reference is had to the accompanying drawings, in which—

Figure 1 is an elevation of my invention. Fig. 2 is a central longitudinal sectional view of the same. Fig. 3 is a top view of the bottle-cap, with the stem removed, on line α α 20 of Fig. 1.

Like parts are identified by the same reference-letters throughout the several views.

A is the bottle, preferably provided with a measuring-gage, as shown in Fig. 1, and having a screw-threaded neck B, over which a metallic cap C is adapted to fit. The cap C is provided with an upwardly-projecting interiorly-screw-threaded thimble D, into which the upper section of the suction pipe or stem

30 is adapted fit. The latter is formed of a glass tube E, covered by a pewter or other metal covering F to protect it from breaking, and having a flange G at its lower end adapted to bear upon the upper end of the thimble D.

35 At its upper end, which is preferably bent, the stem is provided with annular ribs or projections H, adapted to retain the rubber nipple I, which is slipped over the end of the stem and additionally secured by means of a bone ring J. The metal covering of the stem

40 is also provided with oppositely-disposed slots K, thus exposing the glass tube and its contents to view.

The lower section L of the suction-pipe is 45 formed of glass and adapted to be inserted through an opening in the cap C, which is

inclosed by said thimble D, with an annular flange M, adapted to engage the sides of the opening, and a tapering upper end adapted to enter the lower end of the upper section. 50 Packing-rings N and O are preferably used above and below the flange M, and are of such thickness that the end of the upper section will bear tightly upon the packing when the flange G is in contact with the thimble D. 55

The cap C is provided with an eye P to facilitate the attachment of a holding ribbon or cord and small openings Q to admit air to the interior of the bottle. When it is desired to close the openings, a metallic washer R is 60 interposed underneath the cap.

It will be observed that with the above-described construction the parts may be easily separated and kept absolutely clean, there being no rubber parts in contact with the milk 65 except the nipple.

Having thus described my invention, what I claim as new, and desire to secure by Letters Patent, is—

The combination with a bottle, of a cap 70 adapted to fit thereon and having an opening therethrough surrounded by an upwardly-projecting interiorly-screw-threaded thimble, and air-admitting openings exterior to the thimble, together with an eye for the attachment of a holding ribbon or cord, a washer adapted to cover said air-admission openings, a glass tube adapted to fit through said thimble-opening and provided with an annular flange at its upper end adapted to engage 80 the sides thereof, an upper glass tube covered with metal and adapted to screw into said thimble with its lower end in connection with said first-mentioned tube, and a rubber nipple adapted to fit over the free end of the upper tube, substantially as described. 85

In testimony whereof I affix my signature in the presence of two witnesses.

CLARA BORGENSCHILD.
